(57) **CLAIM**

The ornamental design for a “grip for a marker”, as shown and described.

DESCRIPTION

FIG. 1 is a perspective view as seen from the top, front and right side of a grip for a marker showing our new design; FIG. 2 is a front view, the rear view being a mirror image thereof;

FIG. 3 is a right elevational view, the left elevational view being a mirror image thereof;

FIG. 4 is a bottom view thereof; and,

FIG. 5 is a top plan view thereof.

The broken line showing of a marker is for illustrative purposes only and forms no part of the claimed design.
